UNITED STATES PATENT OFFICE.

ARBA M. C. WILSON, OF SALINE, MICHIGAN.

SPARK-PLUG.

1,359,642.

Specification of Letters Patent. Patented Nov. 23, 1920.

Application filed August 14, 1919. Serial No. 317,551.

To all whom it may concern:

Be it known that I, ARBA M. C. WILSON, a citizen of the United States, residing at Saline, in the county of Washtenaw and State of Michigan, have invented certain new and useful Improvements in Spark-Plugs; and I do hereby declare the following to be a full, clear, and exact description of the invention, such as will enable others skilled in the art to which it appertains to make and use the same.

The present invention relates to spark plugs, and aims to provide a novel and improved device of the character which will efficiently ignite the charges within an internal combustion engine, with less liability to become fouled.

Another object is the provision of a spark plug having novel means for intensifying the sparks, and also providing for external inspection to determine whether or not the plug is in working condition, without the necessity of removing the plug or making tests.

25 A further object is the provision of novel spark producing means, and means enabling the spark gap to be adjusted quickly and conveniently.

A still further object is to provide a series 30 of sparks around the inner end portion of the plug, to assure of perfect ignition.

The invention has for its object the provision of the nature indicated, comprising a novel assemblage and construction of the 35 component elements, in order that the device will be thoroughly practical, efficient and reliable in use, as well as being comparatively simple and inexpensive in construction.

With the foregoing and other objects in view, which will be apparent as the description proceeds, the invention resides in the construction and arrangement of parts hereinafter described and claimed, it being understood that changes can be made without departing from the spirit of the invention.

The invention is illustrated in the accompanying drawings, wherein:—

Figure 1 is an elevation of the improved plug.

50 Fig. 2 is a longitudinal section thereof.

In carrying out the invention, there is provided a metallic plug member 1, which is screw threaded to screw into the engine cylinder, as usual, and which is also formed 55 for the engagement of a wrench in applying and removing the plug. The member 1 is

provided at its outer end with a screw threaded counter-bore 2 into which is threaded the inner end of a tubular metallic sleeve or shell 3. An insulator core 4 of porcelain or other suitable insulating material extends through the bore of the member 1, and projects partially into the shell 3 and partially from the inner end of the member 1. This insulator 4 is provided near its inner end with an annular groove 5, and has an enlargement 6 at its inner end. A bushing 7 is fitted on the neck or reduced portion of the insulator 4 within the groove 5, and is screw threaded into the inner end 65 of the member 1, to retain the insulator in place. The insulator can be divided for the purpose of getting the bushing thereon, or the parts can be assembled in any other practical way.

A conducting rod 8 extends longitudinally through the insulator 4, and is provided at its inner end with a head 9, and at its outer end with an electrode terminal 10, and a nut 11 is screw threaded onto the outer end portion of the rod 8 and bears against the outer end of the insulator 4, to firmly clamp said rod within the insulator. This rod serves to conduct the electrical energy through said insulator.

In order to provide multi-spark gap, a metallic washer or ring 12 is clamped within the groove 5 between the bushing 7 and enlargement 6, and a similar washer or ring 13 is clamped between the head 9 and enlargement 6. These washers are provided at their outer edges with annular flanges 14 extending toward one another around enlargement 6, and the edges of said flanges are toothed or serrated, with the teeth or points alternating, so as to provide a continuous annular zig-zag spark gap around the inner portion of the plug. This will provide for the production of a large number of sparks around the plug, to assure of 95 perfect ignition, and the circumference of the enlargement 6 has an annular groove 15 extending around the inner side of the spark gap and electrode points. The washer 12 is clamped in place between the enlargement 6 and bushing 7, and in contacting with said bushing will be in electrical connection with plug number 1, so as to be grounded to the engine whereas the washer 13 is held in place by the head, 9 and will 100 thus be in electrical connection with rod 8. By loosening the rod 8, the washer 13 is

loosened, and can be rotated slightly, for regulating the width of the spark gap by bringing the edges of the electrode points or terminals closer together or farther apart. 5 By separating the washers 12 and 13, the spark gap is also increased. When the plug member 1 is screwed into the cylinder, the sparking or electrode washers 12 and 13 will extend into the chamber of the cylinder, to effectively ignite the charge, and the inner end of the plug is not chambered as usual, so as to avoid the accumulation of carbon as occurs in such a chamber.

A second insulator or core 16 is screw 15 threaded into the outer end of the tubular shell 3, being retained in its adjusted position by means of a lock nut 17 screwed on said insulator and bearing against said end of the shell. The inner end portion of the 20 insulator 16 which extends within the shell, is reduced, as at 18, and fits within a glass or other transparent insulating tube 19, that serves as a lining for the shell 3. This tube 19 is fitted within the shell and extends into 25 the member 1 around insulator 4, so that said tube has its end portions fitted on the adjacent ends of the two insulators, to inclose the spark gap between the insulators. The shell 3 has an opening or window 20 30 across which tube 19 extends, and permitting observation of the intensifying spark gap. A conductor rod 21 in alinement with the rod 8 extends longitudinally through the insulator 16, and is provided at its inner 35 end with conical head 22 seating against the inner end of the insulator 16, and providing an electrode terminal adjacent to the terminal 10 to provide an intensifying spark gap. A binding nut 23 is threaded on the 40 outer protruding terminal of the rod 21 for clamping the conductor wire to complete the electrical circuit.

By the provision of the spark gap between the rods 8 and 21, this will serve to 45 intensify the current and sparks produced between the ignition electrodes at the inner end of the plug, and furthermore, by looking through the opening 20, an indication can be had of whether or not the plug is in 50 working condition. When the plug is in working condition the sparks between the electrode terminals 10 and 22 will indicate this fact, whereas if such sparks are absent, or are of improper character, it will be 55 known that the plug is out of commission.

The gap between the terminals 10 and 20

can be adjusted to suit conditions, by loosening the lock nut 17, and turning the insulator 16 accordingly, after which the lock nut is again tightened, to hold the parts in 60 adjustment.

Having thus described the invention, what is claimed as new is:—

1. A spark plug comprising a plug member, a tubular shell removably secured there- 65 in and extending therefrom, an insulator within said member extending into the shell, a second insulator having a screw threaded connection with the shell and entering same, a conducting rod extending through each 70 insulator, the adjacent ends of said rods having electrode terminals providing an intensifying spark gap, a transparent tube fitted within the shell and on the adjacent ends of said insulators, the shell having an 75 opening exposing the spark gap, and sparking electrodes between said member and rod of the first named insulator.

2. A spark plug comprising a plug member, an insulator therein having an enlarge- 80 ment, a bushing fitted on said insulator and removably secured within said plug member, a conducting rod extending through said insulator, an electrode washer between said enlargement and bushing, a second 85 electrode washer between said enlargement and rod opposite to the aforesaid washer, said washers having coöperating sparking points around said enlargement, and means for clamping said rod to the insulator. 90

3. A spark plug comprising a plug member, an insulator therein having an annular groove, a bushing in said groove engaged with said member, said insulator having an enlargement, a conducting rod extending 95 through the insulator, means on said rod for clamping it in the insulator, an electrode washer between said enlargement and bushing, a second electrode washer between 100 said enlargement and rod opposite to the aforesaid washer, said washers having flanges extending toward one another around said enlargement and provided with sparking points.

In testimony whereof I have signed my 105 name to this specification in the presence of two subscribing witnesses.

ARBA M. C. WILSON.
